GARMENT HANGER

Elenora S. Welch, 12497 Gilmore, Los Angeles, Calif.

Filed Sept. 27, 1960, Ser. No. 62,279

Term of patent 14 years

(Cl. D80—8)

FIG. 1

FIG. 2.

FIG. 3.

FIG. 4.

I claim:

The ornamental design for a garment hanger, substantially as shown and described.
